UNITED STATES PATENT OFFICE.

ROBERT F. BECHT, OF SILVERTON, OHIO, ASSIGNOR TO THE KENTON BAKING POWDER COMPANY, OF CINCINNATI, OHIO, A CORPORATION OF OHIO.

MARKING DEVICE.

Application filed March 26, 1927. Serial No. 178,730.

My invention relates to devices for marking objects, such as cans, on a conveyor.

It is the object of my invention to provide a marking device which may be operated in conjunction with a conveyor at such a ratio of speed that the marking device will be timed with the rate of movement of a continuous line of cans on a conveyor so that each can may be marked with a code or serial number. In such a device or mechanism it is my object to provide a novel arrangement and assembly of parts which will in an entirely automatic manner when properly set in time, with the conveyor, stamp each can at the time when it is moved into alignment with the stamping device.

The above and other objects which will be noted during the course of the ensuing disclosure, I accomplish by that certain arrangement and combination of parts on which I have illustrated a preferred embodiment.

Referring to the drawings:

Figure 1 is a plan view of the assembly with the stamper bar in stamping position.

Figure 2 is a side elevation of the assembly with the stamper bar in re-inking position.

Figure 3 is a perspective view of the stamper bar.

The conveyor on which the cans are carried is supported on standards 1. The mechanism which provides motive power for the conveyor is not shown as it forms no part of my invention. The conveyor has a track 2 extending along it and a chain 3 having interspaced lugs 4 which abut the cans and cause them to move along on the track. The stamping mechanism, which is illustrated, is adapted to stamp the end of each can as it arrives at a position aligned with the stamper bar.

The stamping device which we have shown is composed of a stamper bar 5 carrying at one end a rubber stamp 6. The rubber stamp is moved by the mechanism of the device from a position bearing against the end of a can to a substantially vertical position in which the stamp bears against the inking pad 7 where during each cycle of movement of the stamp is re-inked.

The mechanism which carries the stamp is supported usually from the floor by angle supports 8. The stamping device has a head 9 to which the supports 8 are attached.

The head is divided into two sections and each section has a curved groove 9^a therein which grooves seat the rollers 10 of the stamper bar. The grooves are on the inner faces 11 of the head and extend in alignment. The drive for the stamper bar is from a sprocket 12 which is driven by a chain 13 which may either be driven from the conveying mechanism or from an independent source of power which is timed with the rate of movement of the cans on the conveyor.

The sprocket 12 is mounted on a horizontal shaft 14 on which a beveled pinion 15 is also mounted. The pinion 15 engages a bevel gear 16 which is mounted on a shaft 17 extending through the side wall of the head and into the open space between the divided portions of the head. On the shaft 17 there is a short crank arm 18 which is connected with a long link 19. The link 19 is attached at its end opposite the connection with the crank, with the spindle 19^a or axle of the guide rollers 10. Referring to Figure 3 it will be observed that the link is connected to a forked boss 20 which extends from one side of the stamper bar 5. Thus the crank and link move the carriage for the stamper bar without controlling the angular position of the stamper bar on the carriage.

The end of the stamper bar opposite the part which holds the stamp is bifurcated as at 20^a and a spring shaft 21 which extends through a hole 22 in a plate 23 extended across between the divided parts of the head, is attached in the bifurcated end with a pin 24. A spring 25 keeps the shaft 21 under a normal tension so that the position of the stamper bar, with relation to the carriage, during its cycle of movement, is thus controlled. I have further found it desirable to thread the shaft 21 and to mount thereon a nut 26 which prevents the shaft 21 from pulling the stamper bar from the course of its prescribed movement.

It will be apparent that other means of inking the stamp may be used such as an inking roller, and the stamp may be made of any desired material. Further, other mechanical means for driving the stamper bar will readily occur to those skilled in the art aside from the particular structure which I have illustrated.

The cycle of movement of the stamping device will be obvious. The crank and link move the stamper bar carriage up and down

the grooved supports at a rate timed with the rate of movement of cans on the conveyor and the spring shaft guides the stamper bar from the stamping position illustrated in Figure 1 to the re-inking position shown in Figure 2.

Having thus described my invention what I claim as new and desire to secure by Letters Patent is:

16. 1. A stamping device comprising a stamper bar having an end thereof for the reception of a stamp, said stamper bar having guiding members extending therefrom at angles to the plane of movement thereof, means for actuating said bar connected thereto substantially in alignment with the guides, yielding means for retaining said bar in a prescribed cycle of movement, and said actuating means timed in accordance with the rate of movement of articles to be stamped.
20. 2. A stamping device comprising a stamper bar having an end thereof for the reception of a stamp, said stamper bar having guiding members extending therefrom at angles to the plane of movement thereof, means for actuating said bar connected thereto substantially in alignment with the guides, yielding means for retaining said bar in a prescribed cycle of movement, and said actuating means timed in accordance with the rate of movement of articles to be stamped, said actuating means comprising a crank mounted on a rotatable shaft, and a link extending from said crank connected with said bar.
25. 3. A stamping device comprising a stamper bar having an end thereof for the reception of a stamp, said stamper bar having guiding members extending therefrom at angles to the plane of movement thereof, means for actuating said bar connected

thereto substantially in alignment with the guides, yielding means for retaining said bar in a prescribed cycle of movement, and said actuating means timed in accordance with the rate of movement of articles to be stamped, said actuating means comprising a crank mounted on a rotatable shaft, and a link extending from said crank connected with said bar, and said yielding means comprising a spring controlled shaft connected to said bar at the end thereof opposite that which receives the stamp.

4. A stamping device comprising a member movable through a cycle of movement from a position in which ink is supplied to a stamp carried on said member to a position in which said stamp engages an article to be stamped, and means for moving said member through said cycle of movement comprising a crank and link connected to substantially the central portion thereof and a position governing member connected to an end of said member opposite an end carrying said stamp.

5. A stamping device comprising a member movable through a cycle of movement from a position in which ink is supplied to a stamp carried on said member to a position in which said stamp engages an article to be stamped, and means for moving said member through said cycle of movement comprising a crank and link connected to substantially the central portion thereof and a position governing member connected to an end of said member opposite an end carrying said stamp.

ROBERT F. BECHT.
